TYPEWRITER PLATEN SHIFT LOCK
RELEASEGeorge F. Handley, Glendale, N. Y., assignor to
Royal Typewriter Company, Inc., New York,
N. Y., a corporation of New York

Application August 26, 1936, Serial No. 98,025

7 Claims. (Cl. 197—80)

This invention relates to new and useful improvements in typewriting machines generally, although more particularly to means for releasing the shift lock key lever of telegraph-receiving 5 typewriting machines.

In standard typewriting machines, such as is shown in the Handley Patent No. 1,722,142, July 23, 1929, the shift lock key lever is held depressed by a locking latch, and in order to release the latch from its engagement with the lever it is necessary for the operator to exert a decided downward pressure on said lever. The pressure necessary to release the latch is much greater than the staccato touch employed by the operator 15 when depressing the type bar key levers.

Among the several objects of my invention are to provide a typewriting machine in which the shift lock key lever is releasable by the same kind of staccato touch as is employed in operating 20 the type bar key levers, and to locate the release lever intermediate the type bar key levers whereby by the release lever will be positioned in one of the banks or rows of keys and thereby effect a resultant increase in the speed of operation of the 25 machine.

With these and other objects in view which will more fully appear, the nature of the invention will be more clearly understood by following the description, the appended claims, and the several 30 views illustrated in the accompanying drawings.

In the drawings:

Figure 1 is a vertical longitudinal sectional view of a typewriting machine embodying my invention;

Figure 2 is an enlarged detail view showing the shift lock key lever, the segment shift lever, and the shift lock latch, the parts being shown in their shifted and locked positions;

Figure 3 is a view similar to Figure 2 but showing the special shift release key lever and the segment shift lever fully depressed, and the shift lock lever of the locking latch in their normal positions;

Figure 4 is a detail view showing a modification employed in connection with the special shift release key lever when it is desired to letter space the carriage upon depression of said lever;

Figure 5 is a horizontal view, partly in section, of the keyboard, and showing particularly the special shift release key lever and its associated parts;

Figure 6 is a detail section taken on the line 6—6 of Figure 1;

Figure 7 is an enlarged section taken on the 55 line 7—7 of Figure 1;

Figure 8 is a perspective view of the segment shift lever;

Figure 9 is a perspective view of the shift lock lever;

Figure 10 is a perspective view of the rocker 5 arm; and

Figure 11 is a perspective view of the special type bar.

The invention is illustrated as being applied to a standard Royal machine, although it will be 10 understood that it is capable of being applied to other typewriters.

The drawings disclose a portion of the main frame A, a carriage B having a platen C thereon, and a shiftable segment D. The machine 15 includes type actions which include key levers F and a special release key lever F'. All of these key levers F and F' are fulcrumed at their rear ends on a transverse rod 5 supported by the main frame of the machine, the key levers F being 20 provided at their front ends with finger pieces 6 and the release key lever F' being provided at its front end with a finger piece 6a. The finger pieces 6 are arranged in the usual rows or banks in the key board, and the finger piece 6a of the 25 release key lever F' is preferably located in the first row or bank. Each key lever F and F' is connected by a link 7 to a front link 8 which is connected by a link 9 to an intermediate lever 10 fulcrumed on a cross bracket 11 carried by the 30 main frame, the lever 10 being connected by a link 12 to the heel of the associated type bar which is pivoted on the segment D. The type 35 bar or pivoted arm E which is associated with the release key lever F' is devoid of type as shown in Figures 1 to 11, inclusive, and constitutes a movable weighted element. A shift key lever G which is located on the right hand side of the keyboard, has its rear end fixed to a transverse shaft 13 journaled on the sides 14, 15 of the machine frame A below the key levers F and F'. A shift lever H which is also fixed at its rear end to the shaft 13, is located on the left hand side of the keyboard. The rear end of the lever H terminates in an upwardly extending arm 16 to 45 which is pivoted at 17 a bell crank lever having two arms 18 and 19. The arm 18 is adapted to be link-connected to a latch (not shown) for retaining the segment D in its upper position. The arm 18 is connected by a link 20 which in turn is adjustably connected to a link 21. The link 21 is connected to the vertical arm 22 of a bell crank lever which is fulcrumed as at 23 on the machine frame, the horizontal arm 24 of said lever being connected to the segment D through 50 55

the medium of a vertical thrust link 25, and a coil spring 26 is connected to the arm 24 of said lever and to the machine frame. It will be apparent from the above that when the shift key lever G is depressed, the segment will be lowered against the tension of the spring 26. The shift lever H is provided with a rearwardly and downwardly extending stop arm 27 adapted to contact the bracket 11 to thereby limit the downward movement of said lever.

Secured by a set screw 28 to the left hand end of the shaft 13 between the shift lever H and the machine wall 14, is a collar 29, and journaled on this collar is the rear end of a shift lock key lever I having a finger piece 30 at its front end.

A shift locking member of latch J, of substantially U-shaped construction, has its rear leg 31 pivoted by a screw 32 to the wall 14 at a point in rear of the finger piece 30 of the shift lock key lever I, and has its front leg 33 disposed intermediate the pivot 32 and the finger piece 30. The upper end of the front leg 33 is downwardly and forwardly inclined or cammed as at 34 and is disposed below and in direct contact with a roller 35 journaled on the shift lock key lever I. It will be noted that the legs 31, 33 of the latch J are offset, the rear leg 31 being located between the shift lock key lever I and the wall 14 of the machine frame, and the front leg 33 being located along the right hand side of the lever I. Thus the lever I extends between the legs of the latch J. The front leg 33 of the latch is yieldably retained in engagement with the roller 35 by a coil spring 36 having its rear end connected to the rear leg 31 of the latch and its front end anchored to the frame wall 14.

Extending forwardly from the front leg 33 is an arm 37 having a notched front end 38 adapted for cooperation with a stud 39 which is eccentrically mounted for adjustment on the shift lever H.

Secured to the rock shaft 13 by a screw 40 is a forwardly extending rock arm 41 having an offset or laterally extending arm 42 at its forward end which underlies the release key lever F'. A vertically disposed screw 43 is threaded downwardly into the arm 42 and is retained in an adjusted position by a lock nut 44. The rounded head 45 of the screw is disposed under the release key lever F' and is normally disposed in spaced relation thereto, as shown in Figure 1.

It may or may not be desirable to letter space the carriage when the shift lock is released. If it is not desirable, a link 46 will not be connected 55 to the universal bar 47, as shown in Figure 1. However, if it is desirable to letter space the platen, the link 46 will be connected with the universal bar as shown in Figure 4.

When it is desired to shift the segment D and 60 lock the same in its shifted position, the operator depresses the shift lock key lever I, which through the medium of the locking latch J and stud 39 depresses the shift lever H and rocks the shaft 13, the shaft 13 in turn effecting a lowering of the 65 segment against the tension of the spring 26. When the shift lock key lever I has reached its lowermost position, the notch 38 of the latch J will cooperate with the stud 39 of the shift lever H and lock the latter against upward movement.

When it is desired to release the shift lock, 70 the operator taps the finger piece 6a of the release key lever F' by a staccato touch which causes the pivoted arm or element E to swing upwardly to the position shown in dotted lines in Figure 1, 75 the downward movement of the lever F' under

the influence of the staccato touch terminating just short of the head 45 of the screw 43 which is carried by the rock arm 41. The momentum of the pivoted arm E will cause the latter to move rearwardly beyond its dotted line position 5 and thereby further move the release lever F' into contact with said screw and swing the rock arm 41 downwardly. This downward movement of the rock arm is very slight, but the movement is sufficient to rock the shaft 13 and the shift 10 lever H to thereby release the latch J from its engagement with said shift lever.

As previously stated, the head 45 of the screw 43 is normally spaced below the special key lever F', and the spacing distance is such that the 15 lever will not contact the screw head until said lever has nearly reached the limit of its depression stroke whereby the rock arm 41 will be swung downwardly a very short distance to effect a release of the locking latch J. As a result of this 20 spacing, it will be apparent that the special release key lever F' will require no more pressure to depress the same than the touch required on any of the usual key levers F; that the special type bar or arm E will be swung upwardly during 25 the time the special lever F' is moving downwardly to contact the head of the screw 43; that the upward movement of said special type bar or arm E is an accelerated movement and consequently 30 the momentum attained thereby during the last part of said movement will function to effect a release of the shift lock.

It will, therefore, be seen that the shift lock release is effected by a touch comparable with the touch employed in connection with the usual 35 key levers F.

It is, of course, to be understood that the details of structure and arrangement of parts may be variously changed and modified without departing from the spirit and scope of my invention. 40

I claim:

1. In a typewriting machine, the combination with a cylinder element and a segment element; of means for shifting one of said elements; means 45 for releasably locking the shiftable element in its shifted position; and means for releasing said locking means including a key lever, a pivoted arm, and connections between said key lever and said pivoted arm whereby the momentum of said 50 arm subsequent to the initial depression of the key lever will farther depress the key lever and effect the release of said locking means.

2. In a typewriting machine, the combination with a cylinder element and a segment element; of means for shifting one of said elements; means for releasably locking the shiftable element in its shifted position; and means for releasing said locking means including a release key lever, an arm pivoted on the segment and operatively connected to the release lever, and devices interposed between said release key lever and said locking means for releasing the latter, said devices becoming effective by the momentum of said pivoted arm subsequent to the initial depression 65 of said release key lever.

3. In a typewriting machine, the combination with a cylinder element and a segment element; of means for shifting one of said elements; means for releasably locking the shiftable element in its 70 shifted position; and means for releasing said locking means including a release key lever, an arm pivoted on the segment, a front link, a link connecting the front link and the release key lever, a link connection between the front link 75

and the heel of the pivoted arm, and devices interposed between said release key lever and said locking means for releasing the latter, said devices becoming effective by the momentum of said pivoted arm subsequent to the initial depression of said release key lever.

4. In a typewriting machine, the combination with a cylinder element and a segment element; of means for shifting one of said elements, and for releasably locking the shiftable element in its shifted position including a transverse shaft located in front of the segment, a shift key lever fixed to said shaft and operatively connected to said shiftable element, a shift lever fixed to said shaft, a shift lock lever fulcrumed on said shaft, a latch cooperable with the shift lever and the shift lock lever to lock the element in its shifted position; a rock arm fixed to said shaft; and means for releasing said locking means including a key lever, a pivoted arm, and connections between said key lever and said pivoted arm whereby the momentum of said arm subsequent to the initial depression of the key lever will farther depress the key lever and effect the release of said locking means.

5. In a typewriting machine, the combination with a cylinder element and a segment element; of means for shifting one of said elements and for releasably locking the shiftable element in its shifted position including a transverse shaft located in front of the segment, a shift key lever fixed to said shaft and operatively connected to said shiftable element, a shift lever fixed to said shaft, a shift lock lever fulcrumed on said shaft, a latch cooperable with the shift lever and the shift lock lever to lock the element in its shifted position; a rock arm fixed to said shaft; a vertically adjustable element mounted on said rock arm; and means for releasing said locking means

including a key lever located above and in spaced relation to said adjustable element, a pivoted arm, and connections between said key lever and said pivoted arm whereby the momentum of said arm subsequent to the initial depression of the key lever will farther depress the key lever and effect the release of said locking means.

6. In a typewriting machine, the combination with a cylinder element and a segment element; of a plurality of type bars pivoted on said segment element; means for actuating said type bars including key levers, means including a shift key lever located at one side of the type-bar actuating key levers for vertically shifting one of said elements; means for releasably locking the shiftable element in its shifted position; and means for releasing said locking means including a release key lever, a pivoted arm, and connections between said release key lever and said pivoted arm whereby the momentum of said arm subsequent to the initial depression of the release key lever will farther depress the release key lever and effect the release of said locking means, said release key lever being located intermediate said type-bar actuating key levers.

7. In a typewriting machine, the combination with a cylinder element and a segment element; of means for shifting one of said elements; means for releasably locking the shiftable element in its shifted position; and means for releasing said locking means including a key lever, a movable weighted element, and connections between said key lever and said weighted element whereby the momentum of said weighted element subsequent to the initial depression of the key lever will farther depress the key lever and effect the release of said locking means.

GEORGE F. HANDLEY.
